Primary Examiner—Raphael Barkai*Assistant Examiner*—Randall Gholson(74) *Attorney, Agent, or Firm*—Banner & Witcoff, Ltd.(57) **CLAIM**

The ornamental design for a portion of a television receiver, shown and described.

DESCRIPTION

FIG. 1 is a top, front and right side perspective view of a portion of a television receiver showing my new design,

FIG. 2 is a front elevational view thereof,

FIG. 3 is a top plan view thereof,

FIG. 4 is a left side elevational view thereof

FIG. 5 is a right side elevational view thereof,

FIG. 6 is a bottom plan view thereof,

FIG. 7 is a rear elevational view thereof,

FIG. 8 is an enlarged sectioned end face view take along line A—A with internal mechanism being omitted thereof,

FIG. 9 is an enlarged sectioned end face view of the part partitioned by B—B and C—C thereof; and,

FIG. 10 is an enlarged view of the part partitioned by D—D, E—E and F—F thereof.

The broken lines are shown in the views for illustrative purposes only and form no part of the claimed design.

The part for which the application is filed for a design registration is of transparent material.
